APPARATUS FOR APPLYING GERMICIDE
AND INSECTICIDEThomas W. Brookshire and Samuel McDuffee,
Flora, Ill.

Application January 28, 1935, Serial No. 3,741

3 Claims. (Cl. 299—88)

This invention relates to apparatus and method for applying a germicide or insecticide.

An object of the invention is to provide apparatus, or a spray gun, which is simple in construction, durable in service and easy of operation to apply by compressed air or steam liquid germicide or insecticide.

A further object of the invention is to provide an improved method for applying a liquid germicide and insecticide and which will be effective in reaching remote parts of a room, and in its general usefulness.

Other objects will be apparent from the following detail description of the invention and of the specific embodiment illustrated in the drawing.

Fig. 1 is a plan view of the device;

Fig. 2 is an elevation at the discharge end of the device;

Fig. 3 is a side elevation partly in section; and

Fig. 4 is a detail sectional view.

Apparatus embodying the invention and specifically illustrated in the drawing include a base 1 adapted to engage the wall of a container 2; a straight tubular barrel 3 integrally connected with and supported by the base 1 through a portion 4; a tubular nozzle 5 spaced from the inner walls of the barrel 3 by ribs 6 and its outlet discharging within the barrel a substantial distance from an outlet 7 of the barrel to form a mixing chamber 8; a nipple 9 formed on the inlet end of the barrel and adapted to telescope within a pressure hose; a tube 10 supported by the base 4, as shown in Figs. 3 and 4, and extending within the container 2; and a conduit 11 connecting the tube 10 with the opening in the nozzle 5 and controlled by a valve 12, which has a head 13 so positioned that it may be manipulated by the fingers of a hand engaging a handle 14 which is supported by members 15 attached to or, as shown in the drawing, integral with the barrel 3. One or more helical ribs 16 may be formed on the outside of the nozzle 5 to give a swirl to compressed air or steam passing through the barrel 3 and within the chamber 8 to mix the materials.

It has been found that a liquid germicide, such as a chlorine solution, may be effectively applied by compressed air or steam under substantially high pressure where the liquid is thoroughly mixed with the gas. The same is true with an insecticide, such as a fly spray. In both cases steam is more effective than air.

The foregoing is a summary description of the device illustrated in the accompanying drawing,

while the essential features of the invention are pointed out in the appended claims. A more detail description of the invention and of the embodiment shown will assist in understanding and practicing the invention.

The base 1, as stated, is formed to engage the walls of a container. In the illustrated embodiment it is formed to engage the opening of a glass jar of familiar construction, having a clamp 17, which may be secured over the base as clearly illustrated. It will be understood, of course, that the base 1 may be formed with screw threads to engage a container having screw threads at its outlet, or otherwise formed as desired, the particular attaching means being no part of this invention.

The base 1, barrel 3, connecting member 4, nozzle 5, and handle members 15 may be cast integrally. The channel 11 may be bored through the device to communicate the nozzle 5 with the tube 10. The tube 10 is secured, as shown, by screw threads in an enlarged portion 18 of the channel 11. The upper portion of the bore, which includes the channel 11, is enlarged and screw threaded to receive the shank of the valve member 12. The inlet end of the nozzle 5 is pointed, as shown at 19, to reduce back pressure.

It will be understood that the passage of gas under pressure through the barrel 3 will induce a stream of liquid from the container through the tube 10 and the channel 11, which is controlled by the valve 12. An air vent 20 through the base opens the container to atmosphere and permits this suction to be effective. The nozzle 5 discharging within the barrel permits an effective mixing of the liquid with the gas before it is discharged from the gun or device.

The spray gun has been found effective in applying either a germicide, such as a chlorine solution, or an insecticide, such as a fly spray. This is especially true when live steam is used. When steam is used with a chlorine solution a moist spray results effectively treating the atmosphere and reaching remote parts of a room and any roughened or uneven portions of the wall. The steam condenses on the wall in fine droplets in which condition it is most effective.

In applying a fly spray with steam, the heat and pressure put the flies on the wing and the misty spray is able to more effectively reach the under portion of the wings of the flies, which portion is necessary to be reached.

It is obvious that various changes may be made in the details of construction of the device, within the scope of the appended claims, with-

out departing from the spirit of this invention.

We claim:

1. A spray gun for germicide and the like including a barrel having an inlet connection for pressure hose and an outlet, a tubular nozzle within the barrel spaced from the inner walls of the barrel and opening a substantial distance from said outlet to form a mixing chamber, a base member supporting the barrel and adapted to engage the walls of a container, a tube adapted to extend into the container upon which the base is placed, a valve for opening the tube to the nozzle, and one or more angularly disposed baffles adjacent the nozzle for causing a swirl in the mixing chamber.
2. A spray gun for germicide and the like including a barrel having an inlet connection for pressure hose and an outlet, a tubular nozzle within the barrel spaced from the inner walls of the barrel and opening a substantial distance from said outlet to form a mixing chamber, a base member supporting the barrel and adapted to engage the walls of a container, a tube adapt-

ed to extend into the container upon which the base is placed, a valve for opening the tube to the nozzle, and a helical rib on the nozzle adapted to cause a swirl within the mixing chamber.

3. A spray gun for germicide and the like including a base member adapted to engage the walls of a container, a tubular barrel supported by and above the base having at one end a connection for a pressure hose and at the other end an outlet, a tubular nozzle within the barrel and spaced from the inner walls of the barrel, a handle connected with, parallel to and above the barrel, a tube supported by the base and extending within a container upon which the base is placed, a conduit connecting the nozzle with the tube, and a valve member extending laterally into the barrel, adapted to close said conduit and having manual engageable means thereon adjacent the barrel and below the handle so positioned as to be operable by the fingers of a hand engaging the handle.
